GARMENT OR IRONING PRESS

Ernest Davis, Syracuse, N. Y., assignor to The Prosperity Company, Inc., Syracuse, N. Y., a corporation of New York

Application July 21, 1930, Serial No. 469,484
Renewed May 6, 1933

14 Claims. (Cl. 68—9)

This invention relates to pressing machines, and particularly to automatic means for controlling air flow through one of the pressing elements.

5 The principal object of the invention is to provide a pressing machine having an air flow operating unit which will be controlled automatically from the devices for controlling the operation of the motor means of the press.

10 Another important object is to automatically control an air flow operating unit for a press having operating mechanism which initially closes the press under light pressure and finally under heavy pressure so that air will flow automatically when heavy pressure is released between the pressing jaws and particularly when pressure is released from a high power motor which produces the heavy pressure.

15 A further object is to provide an automatic control, irrespective of what purpose to which it is put, for automatically actuating the control upon release of pressure in a motor.

20 A further object of the invention is to provide an air flow operating means which will be controlled by the air pressure used to operate the press regardless of the position of the motor means.

25 An air flow control which is dependent for its automatic operation on the position of the motor means is shown in my copending application, Sr. No. 456,659, for automatic air flow with high pressure, filed May 28, 1930.

30 The invention consists in the novel features and in the combinations and constructions hereinafter set forth and claimed.

35 In describing this invention, reference is had to the accompanying drawings in which like characters designate corresponding parts in all the views.

40 Figure 1 is a side elevation of a pressing machine with my invention applied thereto.

Figure 2 is a view mostly in section, showing the relation of the control and operating means of the pressing machine shown in Figure 1.

45 My invention is designed primarily for use with pressing machines of the head and buck type which are provided with means for blowing a current of air through one of the pressing jaws, such as the fixed pressing element or buck.

50 A movable pressing jaw or head 10 is suitably mounted on a supporting yoke 11 which is pivoted at 12 to a back leg 13 of a pressing machine frame 14. A fixed pressing element or buck 15 is suitably mounted on a supporting neck 16 which rises from the frame 14.

55 The buck 15 is of the conventional type provided with a porous face, not shown, through which air is blown or drawn, in a manner readily understood by those skilled in the art. Air is supplied to or drawn from the lower pressing

element through a pipe 17, from any suitable source or by any suitable means. Valve means 18 are provided for controlling the flow of air through the pipe 17. The valve 18 is operated by a valve operating motor 19, and operator-operated means such as a foot lever 20 and connecting link 21 are provided for additionally operating the valve 18 by moving the valve operating motor 19 bodily, in a manner which will be described later.

10 The yoke 11 is operated to move the head 10 to open and close the press, by a fluid or low power motor 25 which is pivoted to the pressing machine frame at 26 and to an outstanding portion of a link 27, at 28. The link 27 is pivoted to the yoke 11 at 30.

15 After the press has been closed under initial light pressure by the fluid or low power motor 25, final heavy pressure is applied to the pressing jaws or elements by a fluid or high power motor 35. A piston rod 36 is pivotally connected to the forwardly extending arm of the bell crank 37, and the upwardly extending arm of this bell crank 37 is pivotally connected at 38 with the link 27 to form a toggle through which the motor 35 applies final heavy pressure to the yoke 11 and pressing head 10. A spring 39 is provided to open the press when the pressure in the motors 25 and 35 is relieved or exhausted. This operating mechanism for the press or movable pressing jaw is of the conventional type and forms no part per se of the present invention.

Control mechanism for zero pressure

20 Working fluid, such as air, is supplied to the press through a supply line 40. This supply line connects with a valve casing 41 which contains a normally closed intake valve 42, to prevent the flow of air from the supply line 40 through the valve casing 41. The intake valve 42 is connected by a stem 43 with a normally open exhaust valve 44 having a stem 45 which extends through the end of the valve casing 41. A control, such as a foot operated lever 48 is pivotally mounted on the pressing machine frame at 49. A link member 50 connects with a bell crank 51 which is provided with a cross member 52 for operating the valves 44 and 42 in the valve casing 41.

25 When the operator depresses the foot lever 48 to actuate the connecting link 50 and bell crank 51, the cross member 52 will be moved to displace the valve stem 45 to the right in Figure 2, thus closing the exhaust valve 44 and opening the intake valve 42. This movement of the cross member 52 also operates an exhaust valve 44^a which will be described hereinafter. Opening of the intake valve 42 will permit air to flow from the supply line 40 around the open intake valve 42, through the valve casing 41, and pipe 55 to supply working fluid to the low power motor 60

25 to close the press under initial or zero pressure.

A branch 56, of the pipe 55, leads to the valve casing 60, but air can not escape through 5 this valve casing at this time in the operation of the press since the valve in this valve casing is closed.

The foot lever 48 is provided with a latch 61 which engages an abutment 62 to lock the foot 10 lever in depressed position. Any means for holding the press in initially closed position is contemplated herein.

High pressure operating means

15 The control means for operating the high power motor 35 to apply final heavy pressure to the pressing jaws or elements, is preferably of the two-hand control type which requires the operator to use both hands to apply final heavy 20 pressure. The two-hand control illustrated in Figure 2 comprises valve mechanisms 65 and 66 of identical construction, arranged in series. Each of these valve mechanisms 65 and 66 includes a valve casing containing a normally 25 closed intake valve 67 and a normally open exhaust valve 68, connected together by a rigid link or stem 69. Each exhaust valve 68 is provided with a stem 70, extending through the end of the valve casing. The valves of the valve 30 mechanism 65 are operated by a handle 71 which contacts with the valve stem 70. The valves in the valve mechanism 66 are operated by a handle 72 which contacts with the valve stem 70.

Pressure for operating the high power motor 35 is taken from the supply line 40, through a pipe 75 which preferably leads to a pressure regulating or reducing valve 76. This reducing valve 35 may be dispensed with if desired and hence a by-pass 77, having a control valve 78 therein, may 40 be opened when it is desirable to render the pressure regulating or reducing valve 76 inoperative. Air from the by-pass 77, or from the pressure regulating or reducing valve 76, passes through a pipe 80 to a valve casing 81 containing a normally 45 closed intake valve 82. The intake valve 82 is connected by a stem 83 to a normally open exhaust valve 84 having a stem 85 projecting through the end of the valve casing 81. The valves in the valve casing 81 are operated by a 50 rocker arm 86 which is actuated by a plunger 87. The plunger 87 extends into a diaphragm chamber 88 and is operated by a diaphragm 89, when pressure is applied to the diaphragm chamber 88 from the valve mechanism 65. A pipe 90 55 connects the diaphragm chamber 88 with the valve mechanism 65.

When the operator wishes to apply final heavy pressure to the pressing elements he will move the handles 71 and 72, so as to operate the valve 60 mechanisms 65 and 66 at the same time. Air 65 will flow from the supply line 40 through a pipe 92, around the open intake valve 67, through the casing of the valve mechanisms 66, through a pipe 93, valve casing of the valve mechanism 65, 70 around the open intake valve 67, and pipe 90, to the diaphragm chamber 88 of the valve casing 81. The air pressure behind the diaphragm 89 will operate the plunger 87 and move the rocker arm 86 against the valve stem 85 to operate the valves in the valve casing 81.

When the intake valve 82 in the valve casing 81 is open, air will flow from the supply line 40 through the pipe 75, pressure regulating or reducing valve 76, or by-pass 77, through the pipe 80, open intake valve 82, valve casing 81, pipe

95, and pipe 96 to the fluid motor 35 to operate the same to apply final heavy pressure to the pressing elements. Air cannot escape through the pipes 135 and 96^a since the exhaust valve 44^a was closed when the foot lever 48 was operated 5 to bring the pressing elements together under light pressure.

If the operator attempted to close the press under heavy pressure, without first operating the foot lever 48, to operate the zero pressure motor 10 25, the exhaust valve 44^a would be open and air would escape through the pipes 135 and 96^a to the open exhaust valve 44^a, thus preventing sufficient pressure from building up in the pipe 96 to operate the fluid or high power motor 35. The 15 valve 44^a is primarily intended, however, for use in connection with the air flow features later to be described.

A pressure gauge 97 may be mounted at any suitable point to indicate the pressure applied to 20 the fluid motor 35.

Automatic air flow operating means

A valve 18 is provided to control the flow of air through the pipe 17. The valve 18 is provided 25 with a stem 101 having a collar 102 rigidly secured thereon. A spring 103 between the pipe 17 and the collar 102 holds the valve 18 normally in closed position. The valve 18 is opened by a 30 valve operating motor 19 which contains a piston 105 having a piston rod 106 which contacts with the valve stem 101.

Means are provided in the valve casing 60 to supply air to the valve operating motor 19 so as to operate the valve 18 when the machine is 35 closed under zero pressure and after it has been closed under heavy pressure. The valve mechanism in the valve casing 60 is designed however, so as not to operate the valve operating motor 19 when the press is closed under zero pressure 40 prior to applying final heavy pressure. Thus the air flow is automatically provided before the press opens but is not provided during closing of the press. The valve casing 60 contains a normally closed inlet valve 110 and a normally open 45 exhaust valve 111 which are connected together by a stem. The valve 111 has a stem 112 extending through the top of the valve casing 60. A rocker arm 113 contacts with the valve stem 112 to operate the valves 110 and 111. The rocker 50 arm 113 is locked in operated position by a plunger 114 which extends through the side of a diaphragm chamber 115 containing a diaphragm 116. Air is admitted into the diaphragm chamber 115 through a duct or conduit 120, to apply pressure behind the diaphragm 116. The 55 rocker arm 113 is operated by a plunger 123 extending from a diaphragm casing 124 which contains a diaphragm 125. The diaphragm 116 is therefore holding means which is operable 60 upon opening of the valve 110 by means to be described to retain the valve in open position.

The valve casing 60 also contains a normally open intake valve 130 which is closed, against the tension of a spring, by pressure in a diaphragm casing 131 applied behind a diaphragm 132 which contacts with the stem of the valve 130. The valve 130 is in series with the valve 110 and both of these valves are in series with the valve 42.

When the handles 71 and 72 are operated to supply air to the motor 35, which in the embodiment shown herein is a high power motor, through the pipe 96, air will also be supplied through the branch pipe 135, and pipe 136, to the 75

diaphragm chamber 131. The pipe 136 is provided with a branch pipe 137 which supplies air to the diaphragm chamber 124. This supply of air to the diaphragm chambers 131 and 124 will cause the intake valve 130 to be closed, and will cause the rocker arm 113 to be operated to close the exhaust valve 111 and open the intake valve 110. The diaphragms 125 and 132 are means operated when the press is under final heavy pressure, or specifically operated by the fluid pressure from the motor 35, shown herein as a high power motor, to open the normally closed intake valve 110 and to close the normally open intake valve 130.

At this point in the operation of the mechanism, air will flow from the supply line 40 around the open intake valve 42, valve casing 41, pipe 56, around the open intake valve 110, and through the duct or conduit 120 into the diaphragm chamber 115 to lock the valves 110 and 111 in operated position. The pressure in the diaphragm chamber 131, behind the diaphragm 132 will be sufficient, due to the large area of the diaphragm 132, to hold the valve 130 closed against the tension of the spring and the pressure of the air in the valve casing 60. Since this valve 130 is kept closed no air will be supplied to the valve operating motor 19 and no air flow will result. The valve 130 is then means to prevent the flow of air through the pipe 17 when the press is under final heavy pressure.

When the operator wishes to reduce the pressure of the machine from high pressure to zero pressure to obtain air flow he will hold operated the handle 71, while the handle 72 is released to move to its normal inoperative position shown in Figure 2. This operation of the handle 71 alone will hold the valve 67 open and the valve 68 closed in the valve mechanism 65. This will permit air from the diaphragm chamber 88 to flow back through the pipe 90, around the valve 67, through the pipe 93, and into the casing for the valve mechanism 66 from which it will escape, through the open exhaust valve 68. Air will escape from the diaphragm chamber 88, in the manner just described, faster than air can enter the diaphragm chamber through the conduit connecting it with the valve casing 81. The reduction in the air pressure in the diaphragm chamber 88 will permit a spring 82^a to restore the valves 82 and 84 to their normal position, shown in Figure 2. When the intake valve 82 closes, the supply of air from the pipe 80 and through the valve casing 81 and pipes 95 and 96 to the fluid motor 35 is cut off. When the exhaust valve 84 opens, the air in the fluid high power motor 35 will escape through the passages 96 and 95 into the valve casing 81 from which it will exhaust through the open exhaust valve 84.

The pressure in the fluid motor 35 having been reduced, the pressing elements will be closed under initial light pressure only, by the pressure in the fluid low power motor 25. The pressure in the diaphragm chambers 131 and 124 will also be reduced and the valve 130 will open under influence of its spring. The valves 110 and 111, being locked in position by the pressure in the diaphragm chamber 115, will not be influenced by the reduction in pressure in the diaphragm chamber 124.

When the valve 130 opens, air will flow from the supply line 40, around the intake valve 42, through the valve casing 41, pipe 56, around the open intake valve 110, through the now open valve 130, and hose 145, to the valve operating

motor 19. This supply of working fluid to the valve operating motor 19 will cause the piston 105 to move upwardly to open the valve 18 against the compression of the spring 103.

Air will flow through the pipe 17 and cause air-flow through the buck 15 of the press. It is immaterial, so far as this invention is concerned, in which direction the air flows through the pipe 17, or whether the air flow produces a blowing of air up through the face of the buck, or a suction of air through the buck. Both methods are well-known in the art.

The normally closed valve 110 is also a first means which normally disconnects the operated means 19 from the operating mechanism, or specifically from the motor 35 thereof. The first means also remains in connected position after it has been connected with the operating mechanism. The valve 130 is a second means which is in series between the first means 110 and the operated means 19 and is normally in connected position. Now the diaphragms 125 and 132 constitute means which is actuated during the closing movement of the operating mechanism and so long as the operating mechanism is in closed position, and performs the double function of connecting the first means and disconnecting the second means. Now since the diaphragms 125 and 132 are actuated during the closing movement of the operating mechanism and so long as the operating mechanism is in closed position, the first means and the second means will remain, respectively, in connected and disconnected positions until the operating mechanism opens the press. Upon opening of the press, the first means is held in connected position and the second means returns to connected position so that a completed connection is established between the operating mechanism for the movable jaw 10 and the operated means 19. The operated means 19 is thereupon actuated to perform any function desired thereof. The particular function performed herein is the opening of an air flow control valve 18.

When the operator wishes to open the press, he will release the latch 61 and permit the pedal of the foot lever 48 to rise. This movement of the foot lever 48 will cause the link member 50 to move downwardly, thus rocking the bell crank 51 to cause the cross member 52 to move to the left in Figure 2. The valves 44 and 42 in the valve casing 41 will be moved by the spring shown into normal position with the exhaust valve 44 open and the intake valve 42 closed. The closing of the intake valve 42 will cut off the supply of air from the supply line 40 to the pipes 55 and 56. The opening of the exhaust valve 44 will permit air to exhaust from the cylinder of the fluid motor 25, through the pipe 55 and valve casing 41. Air may also exhaust from the valve casing 60 through the pipe 56 and valve casing 41. Dropping the air pressure in the valve casing 60 will reduce the pressure in the diaphragm chamber 115 so that the valves 110 and 111 may be moved into their normal position by the spring shown, with the intake valve 110 closed and the exhaust valve 111 open.

The press may be opened without obtaining air flow by means of the valve 44^a. When the press is closed under heavy pressure the operator, without releasing the handle 71 releases the locking latch 61 so that the foot lever 48 releases the pressure on the means connecting it with the valves 44 and 44^a; these valves 44 and 44^a are then free to open. The valve 44^a will be opened

by the pressure in the pipe 96^a and when open will provide an exhaust for air through pipes 96, 98^a and 135 from the high pressure motor 35 and through pipes 136 and 137 from the diaphragm chambers 124 and 131. The valve 44 will open and permit air to exhaust from the fluid motor 25. When so controlled, the press will open without operating the air flow.

It will be apparent from the foregoing description that the valve operating motor 19 operates to open the valve 18 and cause air-flow through the buck whenever heavy pressure on the pressing element is relieved and the machine remains closed under light pressure from the motor 25. 10
15 The operator may obtain air-flow at any other time by means of an auxiliary control pedal 20 which operates a link member 21 to move the valve operating motor 19 bodily, and thus actuate the valve 18 regardless of the fact that the 20 piston 105 is not moving relative to the cylinder of the valve motor 19. The hose connection 145 is sufficiently flexible to permit this bodily movement of the valve operating motor 19. Obviously the motor 105 may be used for any desired purpose other than to control the flow of air to a 25 pressing jaw.

Although the mechanism represented by the motor 19, the valves in the valve casing 60 and their associated mechanism, such as the diaphragms 132 and 125 and the motor 35, are associated with a low power motor 25 and its controls, this mechanism will operate in the same manner and as effectively with the motor 35 alone. It is immaterial in one aspect of the invention whether 30
35 the motor 35 serves as a high power motor or is a single motor having a two step movement or a single step motor unassociated with a low power motor 25.

While I have illustrated the preferred embodiment of my invention, various changes and modifications may be made therein without departing from the spirit of the invention as set forth in the appended claims.

What I claim is:

45 1. An air-flow control device for pressing machines, including valve means for controlling the air-flow; control mechanism, including a fluid motor, for operating the valve means automatically in accordance with the operation of the 50 pressing machine; and auxiliary means for operating the valve means including means for bodily moving the motor.

55 2. In a pressing machine in combination cooperative pressing elements one of which is movable toward and from the other; air current means connected with one of the pressing elements to pass a current of air therethrough; means to automatically control said air current means; and means to prevent the automatic 60 operation of the air current means when the pressing elements are together under heavy pressure.

65 3. In a pressing machine in combination cooperative pressing elements one of which is movable toward and from the other; air current means connected with one of the pressing elements to pass a current of air therethrough; means to automatically control said air current means; means to prevent the automatic operation 70 of the air current means when the pressing elements are together under heavy pressure; and operator-operated means to control the operation of the air current means at any time.

75 4. In a garment pressing machine in combination cooperative pressing elements one of

which is movable toward and from the other; air current means connected with one of the pressing elements to pass a current of air therethrough; motor means to operate the movable pressing element to close the press; including 5
10 motor means to move the movable pressing element into preliminary closed position; other motor means to apply heavy pressure to the pressing elements; devices to control the operation of the respective motor means; and mechanism, controlled by the operation of the control devices for the heavy pressure motor means, for controlling the operation of air current means.

5. In a pressing machine in combination cooperative pressing elements, one of which is movable toward and from the other; motor means to operate the movable pressing element to effect light pressure and heavy pressure between the pressing elements; control means for controlling the operation of the motor means to effect light pressure and to release light pressure between the pressing elements; control means for controlling the operation of the motor means to effect heavy pressure and to release heavy pressure between the pressing elements; air current means connected with one of the pressing elements to pass a current of air through the work supported on said pressing element; means to control said air current means; and connections between the heavy pressure control 30 means and the air current control means to effect operation of the latter upon operation of the first to release heavy pressure between the pressing elements, so that the air current control means are operated when the press is closed 35 under light pressure after having been closed under heavy pressure.

6. In a pressing machine in combination cooperative pressing elements, one of which is movable toward and from the other; motor means to 40 operate the movable pressing element to effect light pressure and heavy pressure between the pressing elements; control means for controlling the operation of the motor means to effect light pressure and to release light pressure between 45 the pressing elements; control means for controlling the operation of the motor means to effect heavy pressure and to release heavy pressure between the pressing elements; air current means connected with one of the pressing elements to pass a current of air through the work supported on said pressing element; means to control said air current means; connections between the heavy pressure control means and the air current control means to effect operation of 55 the latter upon operation of the first to release heavy pressure between the pressing elements; and means connected to the control means for the air current means and controlled by the light pressure control means for rendering the control 60 means for the air current means inoperative upon release of the light pressure prior to the release of the heavy pressure.

7. In a garment or ironing press, in combination, cooperative pressing jaws one of which is 65 movable toward and from the other, operating mechanism connected with the movable pressing jaw to apply initial light pressure and final heavy pressure between the jaws, air current means connected with one of the pressing jaws to 70 pass a current of air therethrough, and means to automatically control said air current means when the operating means brings the jaws under final heavy pressure, including means controlled by the operating mechanism when under heavy 75

5 pressure to prevent the flow of air through said jaw when the pressing elements are together under heavy pressure and whereby the air current means is rendered operative when the operating means removes final heavy pressure from the press jaws.

10 8. In a garment or ironing press, in combination, cooperative pressing jaws one of which is movable toward and from the other, operating mechanism connected with the movable pressing jaw to apply initial light pressure and final heavy pressure between the jaws, air current means connected with one of the pressing jaws to pass a current of air therethrough, means to automatically control said air current means when the operating means brings the jaws under final heavy pressure, including means controlled by the operating mechanism when under heavy pressure to prevent the flow of air through said 15 jaw when the pressing elements are together under heavy pressure and whereby the air current means is rendered operative when the operating means removes final heavy pressure from the press jaws, and operator-operated means for controlling the operation of the air current means at any time.

20 9. In a garment or ironing press, in combination, cooperative pressing jaws one of which is movable toward and from the other; operating mechanism connected with the movable pressing jaw, including a light power motor to apply initial light pressure, and a high power motor to apply final heavy pressure; operator-operated means for controlling the motors, air current 25 means connected with one of the pressing jaws to pass a current of air therethrough, and means to automatically control said air current means when the high power motor is actuated, including means controlled by the high power motor when under heavy pressure to prevent the flow of air through said pressing jaw when the pressing jaws are together under heavy pressure and to release the means when heavy pressure is released and whereby the air current flows when the jaws 30 are released from heavy pressure.

40 10. An operating control means for a garment or ironing press comprising, reciprocating motor means having a power and return stroke, normally closed valve means connected with a source of fluid supply, holding means operable upon opening of the valve means to hold the latter open, fluid pressure operated means, a normally open valve means connected in series between the normally closed valve means and the fluid pressure operated means, means operable to close the normally open valve means and to open the normally closed valve means, and means connecting the last named means with the motor means so that actuation of the motor means operates the last named means whereby the pressure operated means is automatically actuated upon the return stroke of the motor means.

45 11. An operating control means for a garment or ironing press comprising, a fluid motor, valve means including an inlet and exhaust valve operatively connected with the motor and with a source of fluid supply to actuate the motor, a normally closed valve connected with a source of fluid supply, holding means operable upon opening of the normally closed valve to hold the latter open, fluid pressure operated means, a normally open valve means connected in series with the normally closed valve and the pressure operated means, means operable to close the normally open valve and to open the normally closed valve.

5 valve, and means connecting the last named means with the fluid motor so that the last named means is operated by fluid pressure in the fluid motor to open the normally closed valve and close the normally open valve whereby the fluid pressure operated means is automatically actuated upon exhausting of fluid pressure from the fluid motor.

10 12. An operating control means for a garment or ironing press comprising, motor means to initially close the press under light pressure and subsequently close the press under heavy pressure; a first valve means operatively connected with the motor means and with a source of fluid supply to actuate the motor means including, an 15 exhaust valve; a second and normally closed valve means connected in series with the first valve means, holding means operable upon opening of the second valve means to hold the latter open, fluid pressure operated means, a third and normally open valve means connected in series between the second valve means and the pressure operated means, means operable to close the third and normally open valve means and to open the second and normally closed valve means upon 20 actuation of the motor means under heavy pressure, and means connecting the last named means with the fluid motor means so that the last named means is operated to open the second valve means and close the third valve means and whereby the fluid pressure operated means is automatically actuated upon return of the fluid motor means to initial light pressure.

25 13. An operating control means for a garment or ironing press comprising, a high power motor, 30 a low power motor; a valve means including, an inlet valve and an exhaust valve operatively connected with the high power motor to actuate the same; a valve connected with the low power motor and a source of fluid supply, a normally closed valve connected with the last mentioned valve, holding means operable upon opening of the normally closed valve to hold the latter open, fluid pressure operated means, a normally open valve means connected in series with the normally 35 closed valve and the pressure operated means, means operable to close the normally open valve and to open the normally closed valve, and means connecting the last means with the high power motor and operable upon fluid pressure therein 40 to open the normally closed valve and close the normally open valve whereby the fluid pressure operated means is actuated upon exhausting of the fluid from the high power motor.

45 14. In a garment or ironing press, in combination, cooperative pressing jaws one of which is movable toward and from the other, operating mechanism connected with the movable pressing jaw to close and open the press, normally closed valve means connected with a source of fluid supply, holding means operable upon opening of the valve means to hold the latter open, fluid pressure operated means, a normally open valve means connected in series between the normally closed valve means and the fluid pressure 50 operated means, means operable to close the normally open valve means and to open the normally closed valve means, and means connecting the last named means with the operating mechanism so that actuation thereof operates the last named means whereby the pressure operated means is automatically actuated upon the opening movement of the operating mechanism.
